UNITED STATES PATENT OFFICE.

HERBERT N. KILBY, OF CLEVELAND, OHIO.

FILTER.

1,229,755.

Specification of Letters Patent. Patented June 12, 1917.

Application filed January 13, 1915. Serial No. 2,069.

To all whom it may concern:

Be it known that I, HERBERT N. KILBY, a citizen of the United States, residing at Cleveland, in the county of Cuyahoga and 5 State of Ohio, have invented certain new and useful Improvements in Filters, of which the following is a specification.

My invention has general application to filters and is in the nature of a locking 10 structure for filters embodying a casing constructed of at least two separable parts, the purpose of the locking structure being to hold the separable parts of this casing in fluid tight engagement.

15 The main object of my invention resides in the provision of a structure whereby the locking devices disposed adjacent each line of jointure of the separable parts of a casing may be successively locked or unlocked 20 as the case may be. Preferably, this locking and unlocking operation is effected in stages so that all of the locks along one line of jointure are simultaneously operated and this operation completed before a similar 25 operation is instituted on the next succeeding set of locks. By this successive locking and releasing structure, considerably less power is required to complete the locking of the entire casing than would be 30 the case where all of the locking members acted simultaneously.

In connection with the locking structure above referred to, my invention also consists in the provision of a single operating 35 unit whereby the locking may be effected in the stages mentioned. My invention also contemplates a further step in that means are provided whereby the movable part of the casing may be moved away from the 40 stationary part by the same operating unit used for releasing the locking structures after this release has been effected.

Still a further object of my invention resides in the locking structure including an 45 inclined surface on one of the separable parts and a locking member arranged to engage this surface at such an angle that it forces the movable against the stationary part by movement of the locking member 50 itself.

The preferred embodiment of my invention is shown in the accompanying sheets of drawings, in which similar characters of reference designate corresponding parts, 55 and in which:

Figure 1 is an end elevation of the filter embodying my invention;

Fig. 2 is a rear elevation of the same with the central portion broken away,

Fig. 3 shows a cross sectional view of the 60 same filter with my invention applied thereto and showing the various parts in release position in broken lines,

Fig. 4 is a fragmentary detail of a portion of my improvement showing its application,

Fig. 5 is a fragmentary perspective showing an arrangement of inclined surface forming a portion of my locking structure, 70 and,

Fig. 6 is a rear view of a slightly modified form of structure from that shown in Fig. 2.

I have chosen to illustrate my invention in connection with a filter employing a vertically disposed stationary plate 1 supported 75 upon end standards 2. Pivotaly mounted as at 3 to the upper portion of the supporting plate 1 is a semi-oval hood member 4, the member 4 and the member 1 forming, in the present instance, the two separable 80 parts of the filter casing body, these parts having any preferred type of fluid tight joint 5 between them.

The semi-oval hood member 4 carries along its upper and lower edges in a position directly adjacent its lines of jointure with the back plate 1, horizontally disposed angle members 6 provided at repeated intervals with lugs 7, these lugs being designed to form a portion of the locking 90 structure to hold this hood member in firm engagement with its supporting member. By reference particularly to Figs. 3 and 5, it will be noted that the ends of these lugs nearest the ends of the vertically extending 95 legs of the angles 6, are on a slight incline to the vertical, as shown at 8, while the outer surface of the remainder of their height is straight, as shown at 8^a. Coöperating with each of these lugs is a locking 100 member designated generally by the numeral 9, each of these locking members being rigidly attached to upper and lower supporting shafts 10 and 11 respectively. The opposite ends of these locking members 105 are each provided with a pair of downwardly extending ears 12, these ears being slotted to receive bearing blocks 13 adjustable inwardly or rearwardly under the influence of the adjusting bolts shown at 14. 110 Rotatably mounted within these bearing blocks of each member 9, is a shaft 15 carrying a roller 16, this roller being itself designed to operate upon the inclined sur-

face 8 and the straight surface 9 of its corresponding lug 7.

Pivotedly mounted between outstanding ears 17 extending rearwardly from the rear side of the plate 1, are cylinders 18, these ears and cylinders being so arranged that they lie adjacent each end of the filter as a whole. These cylinders are provided with inlet pipes 19 and outlet pipes 20 which are designed to control the admission of fluid under pressure to and away from the same to operate upon a piston rigidly attached to a piston rod shown at 21. The upper ends of these piston rods are pivoted to rearwardly and upwardly extending lever arms 22, as is shown at 23, these lever arms being also rigidly mounted upon the shaft 10. Thus it will appear that movement of the piston rods downwardly from the position shown in Fig. 3, will cause a rotative movement of the shaft 10, which will in turn cause operation of all of the locking members disposed along the upper edge of the filter and cause the same to relieve the tight engagement between the upper edge of the hood member 4 and the back plate.

In order that the lower set of locks may also be operated, this operation taking place after the upper set of locks have been operated and also by the same operating unit, I have provided the two extreme ends of the shaft 10 with a second lever shown at 24, these levers being of a bifurcated nature and being provided at their end with cross pins 25 such as shown at 25. These cross pins are designed to operate in the slots 26 in the upper end of each of the connecting rods shown at 27, the length of the slots 26 being such that the pins 25 will travel from one extreme position, as shown in Figs. 1 and 3 to the opposite extreme position, the time interval being such that the unlocking of the upper series of locks will have been completed when this stage is reached. Further movement of the piston rods 21 will cause a continued movement of all of the upper locking members 9 with their shaft and will also begin a complete and similar unlocking operation of each of the locking members 9 disposed along the lower line of jointure of the two parts of the casing. By virtue of the pivotal connections of the connecting rods 28 with levers 29 rigidly attached to the lower shaft 11, these levers 29 correspond in purpose and function with the levers 22 carried by the upper shaft 10. Thus, it will be apparent that these two sets of locks are unlocked in successive stages and consequently the power required for unlocking them in this manner will be much less than if they had been unlocked simultaneously.

In order that the hood member 4 may also be elevated after the completion of the unlocking operations just described, I have

provided the hubs 30 carrying the levers 22 with forwardly and downwardly inclined levers 31, the ends of these levers being provided with a stirrup such as shown at 32. These levers or arms 31 are designed to cooperate with rollers 33 adjustably mounted, as shown, within housing members 34 carried by and slightly overhanging each end of the hood member 4. It will be apparent that the levers 31 operate within the space formed between the ends of the casing 4 and the inside of the end standards 2 and consequently, these rollers 33 are so supported that they slightly overhang the ends of the hood 4. Inasmuch as the hood member 4 is pivoted to the back plate as has been shown at 3 and since the lever arms 31 swing with the shaft 10, the paths of movement of these levers and their points of engagement with the lifting structure carried by the hood, will not be concentric. Therefore, the lever arms 31 have been extended, as shown, and provided with the stirrups 32 in order that the upper limit of travel of the hood may not be extended. Further, it will be noted that the lever arms 31 are so arranged that the distance between their upper edges and the rollers 33 is such that the time interval allowed before they meet, is such that the unlocking of both sets of locks along the two lines of jointure has been completed. In this manner the same operating unit operating the locking structure, may also be utilized after the completion of the unlocking to cause an elevation of the hood member itself.

From this description, it will be apparent that the unlocking of the two sets of locks is done in successive stages and after the completion of the unlocking action, the lifting operation of the hood sets in. This entire operation is accomplished by the use of a single operating unit in the nature of the two cylinders 18 by the admission of pressure to the upper sides of their pistons, which causes a downward movement of their piston rods 21. The rigid connection between the levers 22 and the upper shaft 10 causes an oscillation of this upper shaft, which in turn will release the upper sets of locks. The lost motion connection formed by the pin 25 and slots 26 in the connecting rod 27, is such that unlocking operation of the lower set of locks sets in immediately after the completion of the unlocking of the upper set. After the lower set has been unlocked, the lever arms 31 will have traveled to a position of engagement with the rollers 33 carried by the upper side of the hood member 4 and continued movement of the piston rods 21 will cause an elevation of this hood, which will eventually assume the position shown in broken lines in Fig. 3.

In connection with the inclined surfaces

8 forming a portion of the front face of the lugs 7, attention is directed to the fact that the centers of the rollers 12 are in horizontal alinement with their corresponding shafts 10 or 11 and that the incline 8 terminates when these rollers assume a position of horizontal alinement with their operating shafts. When this position is assumed, the rollers are no longer influenced by the inclined end of the surfaces 8 since they rest upon the straight surfaces 9 and consequently the operating shafts 10 and 11 are relieved of the torsion due to the tendency toward reverse movement by the action of the rollers when riding the inclined surfaces. As a result, when the locks have assumed the position shown in Fig. 3, they will remain in this position of their own accord and a supplemental locking structure for holding them there is unnecessary. However, in order to avoid accidental release of the hood member when in its elevated position, I have provided the upper shaft 10 with a ratchet shown at 35, this ratchet being designed to coöperate with a pawl 36 pivoted in any desired manner.

I have chosen to show my invention as applied to the specific type of filter shown, for the reason that an elevation of the hood 30 to the position indicated in Fig. 3, will expose the entire interior filter element construction in approximately the same amount of space required for the mounting of the filter when in its closed position.

In Fig. 6, I have shown a slightly modified form of construction, in that the locks along each line of jointure are not all operated simultaneously. This modification, therefore, consists in the sectional shafts 37 and 38 replacing the shaft 10 in Fig. 1 and the sectional shafts 39 and 40 replacing the shaft 11 in Fig. 1. Also, the cylinders 18 are shown as being oppositely disposed and, therefore, the cylinder to the right of Fig. 45 6, will operate to unlock a number of the lower locking members in its first stages of operation with the subsequent release of certain of the upper series of locks, while that cylinder shown to the left of Fig. 6 operates in just the reverse manner. Otherwise, the structure is in all respects identical with that previously described.

What I claim, is:

1. In a filter, a separable two part casing, one of said parts being pivotally supported to close upon the other part, a locking means independent of said pivotal support disposed adjacent opposite lines of jointure of the parts of said casing, and means for successively releasing the locking means adjacent the various lines of jointure.

2. In a filter a separable two part casing, one of said parts being pivotally supported to close upon the other part, a locking means independent of said pivotal support dis-

posed adjacent opposite lines of jointure of the parts of said casing, means for successively releasing the locking means adjacent the various lines of jointure, and a single operating unit for actuating said locking means. 70

3. In a filter, a separable two part casing, one of said parts being pivotally supported to close upon the other part, a locking means independent of said pivotal support disposed adjacent opposite lines of jointure of the parts of said casing, and means for successively releasing the locking means adjacent the various lines of jointure and moving one of the parts of said casing away 75 from the other.

4. In a filter, a separable two part casing, one of said parts being pivotally supported to close upon the other part, a locking means independent of said pivotal support disposed adjacent opposite lines of jointure of the parts of said casing, means for successively releasing the locking means adjacent the various lines of jointure and moving one of the parts of said casing away 80 from the other, and a single operating unit for actuating said locking and moving means. 85

5. In a filter, a separable two part casing, the parts being arranged to close one upon 95 the other, a locking means disposed adjacent opposite lines of jointure of the parts of said casing, operating means for said locking means, and lost motion connecting means between said locking and operating 100 means whereby said locking means are successively operated.

6. In a filter a separable two part casing, the parts being arranged to close one upon the other, a locking means disposed adjacent opposite lines of jointure of the parts of said casing, a lost motion connection between the locking means along different lines of jointure, and operating means directly connected to only one of said locking 110 means. 105

7. In a filter, a separable two-part casing, the parts being arranged to close one upon the other, a locking means disposed adjacent opposite lines of jointure of the parts 115 of said casing, a lost motion connection between the locking means along different lines of jointure, operating means directly connected to only one of said locking means, and means operating between one of said locking means and the movable part of said casing to engage the movable casing part for movement after said locking means have been successively released. 120

8. In a filter, a separable two part casing, the parts being arranged to close one upon the other, a locking means disposed along opposite lines of jointure of the parts of said casing, operating means and means actuated by said operating means for releas- 125 130

ing one of said locking means after the other locking means has been released.

9. In a filter, a separable two part casing, the parts being arranged to close one upon 5 the other, a locking means disposed adjacent opposite lines of jointure of the parts of said casing, operating means, and means actuated by said operating means for successively releasing said oppositely disposed 10 locking means and engaging the movable part of said casing for movement after the locking means have been released.

10. In a filter, a separable two part casing, one of said parts being pivotally mounted 15 to close upon the other part, a locking means disposed along opposite lines of jointure of said casing including a plurality of locking members, and operating means for operating all of the members along one line 20 of jointure to either lock or release them from said casing before the members along the succeeding line of jointure are operated.

11. In a filter, a separable two part casing, one of said parts being pivotally mounted 25 to close upon the other part, and locking means for holding the parts of said casing together including inclined surfaces on one of said parts, and lock members arranged to coöperate with said surfaces by being 30 brought into wedging engagement therewith, said inclined surfaces terminating at a point where the parts of said casing are securely locked together to relieve said locked members against reverse movement.

35 12. In a filter, an upright back plate, an oval casing member pivotally mounted to close upon and swing away from said plate, and locking means for locking said casing member against said plate including an operating shaft disposed adjacent the upper and lower meeting edges of said casing member and said back plate, and a plurality of locking members on each of said shafts arranged to engage said casing member to 40 force it against said back plate.

13. In a filter, an upright back plate, an oval casing member pivotally mounted to close upon and swing away from said plate, locking means for locking said casing member against said plate including operating 50 shafts disposed one adjacent each the upper and lower meeting edges of said casing member and said lock plate, a plurality of locking members on each of said shafts arranged to engage said casing member to force it against said back plate, and a lost motion connection between said two shafts so arranged that one set of locking members is operated before motion is imparted 55 to the second set.

14. In a filter, an upright back plate, an oval casing member pivotally mounted to

close upon and swing away from said plate, locking means for locking said casing member against said plate including operating 65 shafts disposed one adjacent each the upper and lower meeting edges of said casing member and said lock plate, a plurality of locking members on each of said shafts arranged to engage said casing member to 70 force it against said back plate, a lost motion connection between said two shafts so arranged that one set of locking members is operated before motion is imparted to the second set, and a single operating unit for 75 operating both sets of locking members.

15. In a filter, a separable two part casing, one of said parts being pivotally mounted to close upon and swing away from the other part, and locking means for locking 80 the parts of said casing together including an inclined surface on one of said parts, and a locking member arranged to engage said surface at an angle to force its part against the other part, said inclined surfaces terminating at a point where said two parts are 85 securely locked together to relieve said member against reverse movement.

16. In a filter, a separable two-part casing, one of said parts being pivotally mounted to close upon and swing away from the other part, and locking means for locking the parts of said casing together including an inclined surface on one of said parts and a locking member on the other part arranged 90 to engage said surface at an angle whereby continued movement of said locking member wedges its part against the other part, said inclined surface terminating at a point where said two parts are securely locked to 100 relieve said member against reverse movement.

17. In a filter, a separable two part casing, one of said parts being pivotally mounted to close upon and swing away from the other part, and locking means for locking the parts of said casing together including an inclined surface on one of said parts, a locking member, a roller adjustably carried by said member, and an operating shaft for 105 said member, said roller and member being arranged to engage said inclined surface to force its part into engagement with the other part, said inclined surface terminating at a point where said two parts are securely 110 locked to relieve said member against reverse movement.

In testimony whereof I affix my signature in presence of two witnesses.

HERBERT N. KILBY.
